CLAIM

The ornamental design for a combination storage
container and play table for interlocking building blocks, as
shown and described.

DESCRIPTION

FIG. 1 is a top plan view of a combination storage
container and play tabel for interlocking building blocks
showing my new design;

FIG. 2 is a front elevational view thereof, showing the
legs of the table in an extended position, with the oppo-
site side being a mirror image thereof;

FIG. 3 is the left side elevational view thereof;

FIG. 4 is the right side elevational view thereof;

FIG. 5 is a front elevational view thereof, showing the
leg of the table in a collapsed position, with the opposite
side being a mirror image thereof; and,

FIG. 6 is a perspective view showing the legs of the
table in extended condition.
